United States Patent Office.

NOAH DUTTON, OF JANEVILLE, WISCONSIN.

Letters Patent No. 64,207, dated April 30, 1867.

CLOG FOR PREVENTING COWS FROM FRISKING THE TAIL WHILE BEING MILKED.

The Schedule referred to in these Letters Patent and making part of the same.

TO ALL WHOM IT MAY CONCERN:

Be it known that I, NOAH DUTTON, of the city of Janesville, in the county of Rock, and State of Wisconsin, have invented a new and improved mode of Preventing Cows from Lashing one in the Face while milking them; and I do hereby declare that the following is a full and exact description thereof, reference being had to the accompanying drawings, and to the letters of reference marked thereon.

The nature of my invention consists in suspending a weight to the tail of the said animal in the most convenient way, without confining myself to any particular mechanical construction of the said weight. I am aware that there are various devices in use for the same purpose, but I am not aware that there are any in use where the inventor relies solely upon the specific gravity thereof.

For convenience I have adopted the form set forth in the drawing under Figure 1, which is constructed in the form of pincers, with jaws *a a* and handles *c c*, enlarged at the lower ends thereof, for the purpose of increasing the weight thereof. The letter *b* represents an elastic ring encircling the said handles just below the said jaws, and used for the purpose of tightening the said jaws to the said tail, or the hair thereof, as the case may be. The said ring I regard as an important feature of this invention, by virtue of which I am enabled to compress the said jaws sufficiently tight to the hair of the said tail to sustain the said weight.

What I claim, and desire to secure by Letters Patent of the United States, is—

The application of a weight or an instrument of specific gravity to a cow's tail while milking her, substantially as described and for the purpose specified.

Also, the ring *b*, in combination with the said instrument or weight, substantially as described and for the purpose specified.

NOAH DUTTON.
